US00D935282S

(12) **United States Design Patent** (10) Patent No.: **US D935,282 S**
(45) Date of Patent: **** Nov. 9, 2021**

(54) **THERMAL REGULATION VESSEL FOR INDIVIDUAL BOTTLE OR OTHER BEVERAGE CONTAINER**

(71) Applicant: **GOLDI HOLDINGS LLC**, Salt Lake City, UT (US)

(72) Inventor: **Jeffrey K. Jackson**, Murray, UT (US)

(73) Assignee: **Goldi Holdings LLC**, Salt Lake City, UT (US)

(**) Term: **15 Years**

(21) Appl. No.: **29/758,529**

(22) Filed: **Nov. 16, 2020**

Related U.S. Application Data

(63) Continuation of application No. 16/150,056, filed on Oct. 2, 2018, and a continuation-in-part of application (Continued)

(57) **CLAIM**

The ornamental design for a thermal regulation vessel for individual bottle or other beverage container, as shown and described.

DESCRIPTION

FIG. 1 is an isometric view of a thermal regulation vessel for individual bottle or other beverage container in accordance with my new design;

FIG. 2 is another isometric view thereof;

FIG. 3 is a side view thereof, which side view is identical to all other side views thereof;

FIG. 4 is a top view thereof; and,

FIG. 5 is a bottom view thereof.

The broken lines represent unclaimed subject matter and form no part of the claimed design.
